UNITED STATES PATENT OFFICE.

LOUIS BURGER, OF CHICAGO, ILLINOIS.

DESIGN FOR A BADGE.

SPECIFICATION forming part of Design No. 22,317, dated April 4, 1893.

Application filed February 28, 1893. Serial No. 464,112. Term of patent 3½ years.

To all whom it may concern:

Be it known that I, LOUIS BURGER, a citizen of the United States, residing at Chicago, in the county of Cook and State of Illinois, have 5 invented and produced a new and original Design for a Badge, of which the following is a description.

The drawing illustrates one face of the badge embodying my design.

10 The leading feature of my design consists in the outline representation of one face of a casket having marked thereon spaces in which appear the representations of the head and bust of Columbus, Queen Isabella and a 15 pal ace, respectively.

In the upper part of the representation of the casket pearls are shown in the position of

protruding from the case. Beneath the pictures described the badge is given the outline representation of the ornamental base of a 20 casket and pendent therefrom is the representation of the globe. The badge is shown as surmounted by the representation of the American eagle with wings outstretched carrying flags in its talons, and the upper edge 25 of the badge is shown as beaded.

What I claim as new, and desire to secure by Letters Patent, is—

The design for a badge substantially as shown and described.

LOUIS BURGER.

In presence of—

M. J. FROST,
W. N. WILLIAMS.
